CLAIM

The ornamental design for a mobile phone, as shown and described.

DESCRIPTION

1-2 Mobile phone
1.1: Front
1.2: Back
1.3: Left
1.4: Right
1.5: Top
1.6: Bottom
2.1: Front
2.2: Back
2.3: Left
2.4: Right
2.5: Top
2.6: Bottom

(Continued)

1.1 to 1.6 are six orthographic projection views of a mobile phone of our new design in a folding state; **2.1 to 2.6** are six orthographic projection views of the mobile phone in an expanding state.

In the reproductions, the broken lines are for the purpose of illustrating portions of the mobile phone that form no part of the claimed design.

1 Claim, 12 Drawing Sheets
